UNITED STATES PATENT OFFICE.

JOHN J. TOWER, OF BROOKLYN, NEW YORK.

DESIGN FOR A WRENCH-HANDLE.

SPECIFICATION forming part of Design No. 20,932, dated July 14, 1891.

Application filed May 29, 1891. Serial No. 394,548. Term of patent 14 years.

To all whom it may concern:

Be it known that I, JOHN J. TOWER, a citizen of the United States, residing at Brooklyn, in the county of Kings and State of New York, have invented a Design for a Wrench-Handle, of which the following is a specification.

The leading feature of this design for a wrench-handle consists in the parallel flat surfaces, with the compound curved edges and rounded end and a rectangular jaw at the other end.

In the drawings, Figure 1 is a side view, and Fig. 2 a cross-section at the line $x x$.

The sides $a b$ of the handle are flat and the

outline is a compound curve, as at $c d$, and a plain rounding end at e , and the edges are sectionally arcs of circles, as shown in Fig. 2, and the other end of the handle terminates with a rectangular jaw, as shown. 20

I claim—

The design of the shape and configuration of the wrench-handle, substantially as shown and described.

Signed by me this 26th day of May, 1891.

JOHN J. TOWER.

Witnesses.
